CLAIM

The ornamental design for a crossbody bag, as shown and described.

DESCRIPTION

FIG. 1 is a front view of a crossbody bag showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a first perspective view of a crossbody bag thereof; and,

FIG. 8 is a second perspective view of a crossbody bag thereof.

The broken lines shown in the drawings depict portions of the crossbody bag that form no part of the claimed design.

1 Claim, 8 Drawing Sheets
